SHIELDED TUBE MOUNTING

Scipione M. Del Camp, Maywood, Ill., assignor to
 Cinch Manufacturing Corporation, Chicago, Ill.,
 a corporation of Illinois

Application December 20, 1944, Serial No. 569,076

9 Claims. (Cl. 250—27.5)

The present invention relates to shielded mountings for radio and like tubes and aims generally to improve existing constructions of that type.

One of the primary objects of the invention is the provision of an improved tube socket mounting and shielding cover which will be simple in construction and efficient in operation to prevent resonance and vibration in high frequency circuits.

A further object of the invention is the provision of an improved tube socket mounting, particularly for small miniature base tubes, that eliminates the necessity for separate fastenings, such as screws, rivets and the like, and one that provides means for engagement with a shielding cover to hold the cover tightly against the chassis or support.

Other objects and advantages of the invention will be apparent to those skilled in the art from a consideration of the accompanying drawings and annexed specification illustrating and describing a preferred embodiment of the invention.

In the drawings:

Fig. 1 is a side elevation of a typical miniature base tube installation embodying the invention;

Fig. 2 is an enlarged horizontal sectional view thereof as taken on the line 2—2 of Fig. 1;

Fig. 3 is an enlarged vertical sectional view of the installation as taken on the line 3—3 of Fig. 2;

Fig. 4 is a detail perspective view of the tube socket mounting ring or saddle;

Fig. 5 is a perspective view of the shielding cover; and

Fig. 6 is a horizontal sectional view of the shielding cover as taken through the saddle lug-receiving slots thereof.

Referring more particularly to the drawings, the tube socket mounting and shield support advantageously comprise a saddle which may be a ring-like member adapted to engage the socket over a flange thereof, and retain the socket in operative position on an apertured chassis by means of bendable arms or wings forming a part of the saddle, the saddle having means such as lugs or tabs to engage and hold the shielding cover.

In the illustrated embodiment the chassis 1 may be formed with a suitable aperture 2 to receive the body portion 3 of a socket member of suitable design. Such socket members are preferably formed with an outwardly extending rim or bead 4 and customarily are provided with a plu-

rality of tube prong-receiving apertures 5 having contacts 6 which may be connected to the various electrical circuits of the apparatus. The chassis aperture 2 is of a size to receive the body 5 of the socket but of less diameter than the bead or rim 4 so that the socket is supported in the chassis aperture by engagement of the rim 4 with the upper surface of the chassis. The chassis 1 may be further provided with a plurality of notches or recesses 7 communicating with the aperture 2.

The socket member 3 is retained in position in the aperture 2 of the chassis 1 by means of a thin ring-like saddle member 10 overlying the rim 4 and formed with angularly extending arms 11 adapted to extend through the notches 7 of the chassis and be bent outwardly under the chassis as illustrated in Fig. 3. Thus the rim 4 of the socket member is securely clamped between the chassis 1 and the saddle member 10 by a simple mounting that avoids the necessity of separate fastenings such as rivets, screws and the like.

The socket 3 customarily supports the tube 8 of the electrical apparatus and electrically connects it to the circuits of the apparatus through the usual tube prongs which are inserted in the openings 5 and connect with the contacts 6.

It is frequently desirable in such electrical apparatus to provide a shielding cover for the tube 8 and this is particularly desirable in high frequency circuits.

The shielding cover or can 15 is of a size to enclose the tube and carries an inner coiled spring 16 adapted to engage the outer end of the tube 8 and press it securely against the socket 3. The cover 15 has an inner open end adapted to surround the socket 3 and make a grounded contact with the chassis 1, and preferably this open end of the cover 15 may be outwardly flanged as at 17 to provide a substantial area of contact with the chassis and effect a good ground connection therewith.

According to the invention, the shielding cover 15 is retained in operative position over the tube 8 and in grounding connection with the chassis by means of a locking element on the saddle for locking engagement with the can.

According to the illustrated embodiment of the invention shown in the drawings, the saddle is provided with one or more lugs or tabs 12 as illustrated in Fig. 4, and these tabs preferably extend laterally and radially beyond the periphery of the saddle ring 10.

The sides of the shielding cover or can 16, adjacent the open end, are longitudinally slotted as

at 13, as by forcing the metal of the sides outwardly for a limited depth to permit the open cover to be positioned over the saddle ring 10 and lugs 12. These longitudinal slots 18 communicate with arcuate cam-shaped or inclined slots 19 adapted to receive the lugs 10 upon rotation of the shield about the socket. The ends of the slots 19, remote from the slots 18, may be depressed to provide seats 20 for the lugs 12 so that the cover will be retained in its tightened position against the chassis. As will be apparent in Fig. 1, the arcuate slots 19 are inclined away from the flanged base end 17, so that as the shielding cover is rotated around the saddle, the lugs 12 ride on the inclined faces 19a at the edges of the slots 19, to force the flanged end of the cover 15 into tight grounding engagement with the chassis. The slight notches 20-20 at the ends of the slots 19 receive the lugs 12-12 tightly to prevent accidental unfastening.

From the above it will be apparent that the invention provides a new and improved socket mounting in the form of a saddle that may be attached to a chassis without additional fastenings such as screws, rivets and the like and which is provided with means to engage and hold a shielding cover tight against the chassis to reduce resonance and vibration in high frequency circuits.

The invention is not to be restricted to the specific embodiment shown in the drawings as the scope of the invention is best defined in the appended claims.

I claim:

1. A shielded tube mounting comprising an apertured support, a tube socket mounted in said support, a retaining saddle engaging said socket and connected with said support to retain the socket against displacement from the support aperture and a shielding cover surrounding said socket and having interlocking engagement with said saddle for maintaining contact between said cover and said support.

2. A shielded tube mounting comprising an apertured support, a tube socket mounted in said support, a retainer member engaging said socket and connected with said support to retain the socket against displacement from the support aperture and a shielding cover surrounding said socket and a pin and slot connection between the retainer and cover for maintaining the latter in contact with the support.

3. A shielded tube mounting comprising an apertured support, a tube socket mounted in said support, a saddle member overlying a portion of said socket and having portions extending through

the aperture of said support for engagement with the under side thereof to retain the socket against displacement from the support aperture and a shielding cover surrounding said socket and having interlocking engagement with said saddle member for maintaining contact between said cover and said support.

4. A shielded tube mounting comprising an apertured support, a tube socket mounted in said support, a ring-like member overlying a portion of said socket, said ring member having depending arms extendable through said support aperture and bendable into engagement with a face of the support to retain the socket against displacement from the support aperture and a shielding cover surrounding said socket, and having interlocking engagement with said ring member for maintaining contact between said cover and said support.

5. A tube socket and shield retainer comprising an annular saddle formed with a plurality of arms depending from a peripheral edge thereof, said saddle also having a plurality of shield-engaging lugs extending outwardly from a peripheral face thereof.

6. A tube socket and shield retainer comprising a thin sheet metal ring formed with a plurality of support-engaging arms depending from a peripheral edge thereof, and shield-engaging lugs extending radially beyond the outer periphery of said ring.

7. A tube socket and shield retainer comprising a thin sheet metal ring formed with a plurality of support-engaging arms depending from a peripheral edge thereof, and shield-engaging lugs extending radially beyond the outer periphery and disposed substantially in the plane of said ring.

8. In combination, an annular sheet metal member, means for attaching said member to a support, radially extending lugs on said annular member, a tubular shield having an open end adapted to be positioned over said annular member, the sides of said shield adjacent the open end thereof being formed with longitudinal and segmental slots to receive said lugs.

9. In combination, an annular sheet metal member, means for attaching said member to a support, radially extending lugs on said annular member, a tubular shield having an open end adapted to be positioned over said annular member, the sides of said shield adjacent the open end thereof being formed with longitudinal and inclined segmental slots to receive said lugs.

SCIPIONE M. DEL CAMP.
